UNITED STATES PATENT OFFICE

110,829

DESIGN FOR A DRESS

Anna Wexler, New York, N. Y.

Application June 21, 1938, Serial No. 77,963

Term of patent 3½ years

To all whom it may concern:

Be it known that I, Anna Wexler, a citizen of the United States and a resident of the city of New York, in the county of New York and State of New York, whose post office address is 235 West 102nd Street, city and State of New York, have invented a new, original, and ornamental Design for a Dress, of which the following is a specification, reference being had to the accompanying drawing, constituting a part thereof:

The characteristic feature of my design resides in the combination on the dress disclosed of the specific embroidery arranged on the double collared blouse and on the pleated skirt as shown.

Fig. 1 is a front view of a dress showing my new design.

Fig. 2 is a rear view of the dress shown in Fig. 1.
I claim:

The ornamental design for a dress, substantially as shown and described.

ANNA WEXLER.
